UNITED STATES PATENT OFFICE.

HENRY C. MANCHESTER, OF SCRANTON, PENNSYLVANIA.

WATER-GAGE.

1,070,620.

Specification of Letters Patent. Patented Aug. 19, 1913.

Application filed January 13, 1913. Serial No. 741,636.

To all whom it may concern:

Be it known that I, HENRY C. MANCHESTER, of Scranton, in the county of Lackawanna and State of Pennsylvania, have invented a certain new and useful Improvement in Water-Gages, of which improvement the following is a specification.

My improvement relates to water gages for steam boilers, of the glass tube type, and its object is to provide an appliance of said type, of such construction that engineers and firemen shall be protected from injury in the event of the bursting of a tube, and in which the packing glands of the tube may be set and maintained absolutely in line, and standard lengths of glass tubes, having their ends properly smoothed by being fused, may be held without the degree of liability to leakage or breakage which obtains in ordinary practice.

Incidental objects are simplicity and inexpensiveness in construction, positiveness in action, durability and reliability in service, readiness of application under existing conditions of location of boiler connections, and compliance with the requirements of the Interstate Commerce Commission, and the several State Railroad Commissions.

The improvement claimed is hereinafter fully set forth.

In the accompanying drawings: Figure 1 is a front view, in elevation, of a water gage, illustrating an embodiment of my invention; Fig. 2, a vertical longitudinal central section through the same; Figs. 3, 4, and 5, horizontal sections, on an enlarged scale, on the lines *a a*, *b b*, and *c c*, respectively, of Fig. 2; and, Figs. 6 and 7, partial vertical longitudinal central sections, illustrating modifications of structural detail.

Referring first to Figs. 1 to 4 inclusive of the drawings, in the practice of my invention I provide a gage glass support and shield, 1, which is an integral or "one piece" frame, of symmetrical contour, that is, of circular or polygonal cross-section, having tubular connection chambers, 1^a, 1^b, formed upon and projecting, in line axially, from its opposite ends, said chambers being threaded for connection with upper and lower gage cocks, 2, and being carefully machined so that their axes shall be accurately in line. The upper and lower members of the frame, on which the chambers, 1^a, 1^b, are formed, are connected by a plurality of vertical ribs or bars, of the form in

transverse section shown in Fig. 5, each of said ribs having a longitudinal groove machined in each of its sides, said grooves serving to receive and hold shield plates, 3, of heavy glass, or other suitable transparent material, which extend across the spaces between the ribs, throughout the length thereof, and serve to protect the engineer and fireman from injury by flying fragments of the glass gage tube hereinafter described, in the event of the bursting thereof.

The shield being, as before stated, of symmetrical contour, any one of the spaces may be turned to the front when in position for use.

In the instance shown, four shield plates are provided, that next the front being of plain or clear glass. These plates may be either of plain or of wire netting inserted glass, as preferred, and the rear side shield plate may be faced with any suitable reflector, or may be a perforated plate or woven wire netting, 3^a, preferably set in a frame, 3^b, adapted to fit in the adjacent grooves of the support and shield, 1. A shield plate of this form will permit the escape of steam and water from a broken tube and prevent fragments of the tube from flying out and doing injury. The character and specific number of the shield plates, are not, however, essentials of my invention.

A packing gasket, 4, of rubber or other suitable material is fitted in the inner end of each of the connection chambers, 1^a, 1^b, said gaskets surrounding a gage tube, 5, of strong and well annealed glass, the ends of which extend outwardly, for a short distance beyond the gaskets, and the upper end of which is not in contact with any other member of the appliance, so that no longitudinal or compressive strain is exerted upon the tube. The gage tube being, as before described, completely surrounded by a casing of metal and heavy glass, it is protected against changing atmospheric conditions, so that it cannot be chilled and broken by drafts of cold air to which the tubes of water gages of ordinary construction are subjected.

Upper and lower gage cocks, 2, are connected to the shell, A, of the boiler, in the usual manner, and the body of the lower gage cock is connected directly with the lower connection chamber, 1^b, of the support and shield, 1, through a threaded lateral nozzle, 2^a, which engages the thread of the lower connection chamber and serves as a gland

for said chamber similarly to an ordinary stuffing box gland. As shown in Fig. 2, the lower end of the gage tube, 5, is supported, without being subjected to any compressive strain, on an annular shoulder at the top of of a valve block, 7, fitted between the lower connection chamber and the nozzle, 2^a, of the lower gage cock, but in cases where the check valve device hereinafter described is not applied, it may be similarly supported on a shoulder in the nozzle, 2^a, as shown in Figs. 6 and 7. The upper gage cock is connected indirectly with the upper connection chamber, 1^a, through the intermediation of an extension tube, 6; the upper end of which fits freely in the lateral nozzle, 2^a, of the body of the cock, and the lower end of which is threaded to engage the upper connection chamber, 1^a, of the support and shield, 1. The joint between the extension tube and the nozzle of the cock is made tight by a packing gasket, 6^a, surrounding the tube and compressed against the end of the nozzle by a union coupling nut, 6^b, engaging a thread on the nozzle. The lower end of the extension tube is threaded for engagement with the upper connection chamber, either indirectly, as shown in Fig. 2, and herein-after described, or directly, as shown in Figs. 6 and 7. In the latter case, it bears on and compresses the packing gasket of the upper connection chamber, when screwed to the chamber, and its bore freely surrounds, but has no end bearing on, the upper end portion of the gage tube, 5. The upper end of the extension tube projects into, without end bearing against, the nozzle of the upper gage cock. A removable plug, 2^b, is screwed into the body of the upper gage cock, and a drain cock body, 2^c, controlled by a suitable cock, of the ordinary construction is screwed into the body of the lower gage cock, the passages through the plug and drain cock body being both in line axially with the gage tube. By the removal of the plug, 2^b, a straight and direct passage through the gage tube and the bodies of the gage cocks, is provided, enabling a wire to be run through the gage tube as required by law.

When the extension tube is connected to the upper connection chamber through the intermediation of a valve chamber, 9, as shown in Fig. 2, and herein-after described, it exerts, through said chamber, bearing pressure on the upper packing gasket, 4, with the same effect as if directly connected as in Figs. 6 and 7.

It will be seen that the provision of the extension tube as a connecting medium for the gage support, and the upper gage cock, enables gage tubes of determined standard length, fused smooth at both ends, to be used, without limitation to existing distances between upper and lower gage cocks,

as any variation of distances may be compensated for by corresponding variation in the length of the extension tube.

In the application of my invention to a steam boiler, the unitary support and shield, 1, its shield plates, 3, the glass tube, 5, the packing gaskets, 4, and 6^a, the extension tube, 6, and the nut, 6^b, are first assembled in any convenient location away from the boiler, the extension tube being screwed to the upper connection chamber with a sufficient bearing to compress the packing gasket, 4, of said chamber and seal its joint therewith. The assembled members are then connected to the gage cocks, 2, on the boiler, by passing the extension tube, 6, into the nozzle, 2^a, of the upper gage cock, and screwing the support and shield upon the nozzle of the lower gage cock, until the lower packing gasket, 4, is compressed sufficiently to seal both the glass tube and the screw threads at the connection against leakage. The nut, 6^b, is then screwed on the nozzle of the upper gage cock, compressing the packing gasket, 6^a, and sealing the joint of the tube therewith against leakage, and the gage will be in readiness for service.

The appliance hereinbefore described constitutes, in and of itself, a complete and advantageously operative water gage, and while, without additional members, it is applicable under all the conditions of steam boiler service, it is preferably provided with means whereby the discharge of steam and water from the boiler, resultant upon the breakage of a gage tube, may be automatically and immediately stopped. To this end, a self closing check valve device may, without departure from the essential structural and operative principles of the appliance as before described, be interposed between the ends of the gage tube and the gage cocks. The lower connection chamber, 1^b, is, for the application of this device, made of greater length than is necessary when it is not used, and a valve block, 7, is fitted therein, the top of said block, which may be, as indicated, formed in a separate piece, abutting against the lower packing gasket, 4, and the complete block forming a support for the bottom of the gage tube, 5, and serving as a gland for the chamber, in the same manner as does the nozzle of the lower gage cock when the check valve device is not applied. The connection chamber is screwed to said nozzle and the packing gasket thereby compressed, as in the instance first described. An inclined transverse guide way, 7^a, extends across the valve block, in which there is formed a lower passage, 7^b, extending to said guide way, and a valve seat, 7^c, surrounds an upper passage extending through the top part of the block, both of which passages are in line axially with the gage tube, 5. A small

lateral port, 7^a, also extends from the face of the guide way to the opposite end of the valve block, and a ball check valve, 8, is fitted to traverse freely over the guide way, resting normally at the lower end thereof, as shown in Fig. 2. In the event of the breakage of a gage tube, and the consequent release of steam and water therefrom, the pressure in the boiler, acting through the lateral port, 7^a, on the check valve, 8, will force said valve against the valve seat, 7^c, and prevent further escape of water from the broken tube.

The extension tube, 6, is connected to the upper connection chamber, 1^a, through the intermediation of a valve chamber, 9, which is threaded, at its upper end, to engage the extension tube, and, at its lower end, to engage the connection chamber, for which it forms a gland, and compresses the upper packing gasket, 4, in the same manner as does the extension tube, when directly connected as before noted. A port, 9^a, is formed in a transverse partition, 9^b, in the valve chamber, in line axially with the extension tube and gage tube, the partition being inclined on one side of the port to form a support on which a floating plate, 10, which is a thin metal disk, rests and is normally held in inclined position, by a spring, 11. A guide way, 10^a, is cut in the floating plate, and a ball check valve, 12, which normally rests on the partition, 9^b, is adapted to traverse in said guide way toward and from a seat surrounding the upper end of the partition port, 9^a. The sides of the floating plate are bent upwardly to form lateral guards, and a stop is turned upwardly at the inner end of the guide way, to prevent the check valve from rolling beyond its seat over the partition port. So long as there is an equalization of pressure above and below the floating pan, as in the normal operation of the water gage, the pan is held in the inclined position shown, by the spring, and the ball valve rests entirely clear of the partition port, 9^a. Upon the breakage of the gage tube, and the consequent release of pressure below the floating pan, the downward pressure of steam upon the latter forces it downwardly, against the resistance of the spring, and the check valve rolls to its seat on the upper end of the partition port, 9^a, against which it is firmly held by the boiler pressure, preventing the further escape of steam. The check valves of both the upper and lower ends of the gage tubes, when in normal position, stand entirely clear of the passages which they govern, and therefore do not obstruct the straight way passage through the gage tube.

Figs. 6 and 7 illustrate modifications of detail in the connection of the gage glass support and shield with the extension tube and lower gage and in the location of the

gage tube packing gaskets, all embodying the same structural and operative principles as the construction hereinbefore described. As shown in Fig. 6, the upper packing gasket of the gage tube is fitted within the lower end of the extension tube, and is held between a shoulder in the latter and a flanged ring, 4^b, fitting in a recess in the upper connection chamber, 1^a. The lower connection chamber is threaded inwardly as in Fig. 2, and the lower packing gasket is fitted in the lateral nozzle of the lower gage cock, and held between a shoulder therein and a ring, 4^c, fitting in a recess in the lower connection chamber, in a manner similar to the clamping of the upper gasket. In the form shown in Fig. 7, the gaskets are similarly located, but both the upper and the lower connection chambers are outwardly threaded, and the rings, 4^b, and 4^c, are not applied.

It will be seen that the construction of a water gage embodying my invention is such that it can be easily and inexpensively manufactured in an ordinary foundry and machine shop, without requiring special equipment, and that, when fitted properly, the packing glands of the gage tube are absolutely in line axially and will so remain during the life of the appliance. The assembled members of the appliance can be readily applied to the boiler gage cocks, and it is necessary for the operator to work over a hot boiler only very briefly, as the gage can be applied or removed in the space of about one minute. If the gage tube should break in service, the gage cocks are closed against steam and water leakage, and the support and shield, with the connected members, are removed to a location away from the boiler, where a new gage tube can be inserted. This capacity overcomes the existing objections of working near a hot boiler or in the region of escaping steam, and there is no necessity of removing engaging ends from gage cocks packing glands or digging out packing washers from the hot packing glands, which is difficult and dangerous in ordinary constructions. An important feature of advantage in service consists in the fact that as the shield forms the support of the gage tube, the engineer is obliged to leave the former in operative position on the boiler. In other words, it must necessarily be applied, and it is impossible for the engineer to remove it, if for any reason he should desire to do so, without putting the entire appliance completely out of service.

I claim as my invention and desire to secure by Letters Patent:

1. In a water gage for steam boilers, the combination of an integral frame, comprising two end members, each having formed upon it an outwardly projecting connection chamber, and a plurality of grooved connecting bars, the connection chambers being

- threaded in line axially for connection to upper and lower gage cocks, shield plates fitting in the grooves of the frame bars, a gage tube fitting freely in the connection chambers, packing gaskets surrounding the gage tube in said chambers, and an extension tube connected to one of the connection chambers and bearing on the packing gasket thereof, and free for sliding movement at 10 and adjoining its opposite end.
2. In a water gage for steam boilers, the combination of an integral frame, comprising two end members, each having formed upon it an outwardly projecting connection 15 chamber, and a plurality of grooved connecting bars, the connecting chambers being threaded in line axially for connection to upper and lower gage cocks, shield plates fitting in the grooves of the frame bars, a 20 gage tube fitting freely in the connection chambers, packing gaskets surrounding the gage tube in said chambers, an extension tube connected to one of the connection chambers and bearing on the packing gasket 25 thereof, and free for sliding movement at and adjoining its opposite end, and a gage cock connected to the other chamber and exerting pressure on the packing gasket thereof.
3. In a water gage for steam boilers, the combination of an integral frame, comprising two end members, each having an outwardly projecting connecting chamber, and a plurality of grooved intermediate bars, 35 spaced diametrically to clear a central gage tube, the connecting chambers being threaded in line axially, shield plates fitting in the grooves of the frame bars, an extension tube, the major diameter of which is less than the 40 distance between the shield plates and which is threaded at one end to engage one of the connection chambers and free for sliding movement at and adjoining its opposite end, a gage tube fitting freely in the connection 45 chambers and packing gaskets surrounding the gage tube in the connection chambers.
4. In a water gage for steam boilers, the combination of an upper and a lower gage cock, each having a threaded lateral nozzle 50 on its body, an integral frame, comprising two end members, each having an outwardly projecting connecting chamber, and a plurality of grooved intermediate bars, the connecting members being threaded in line axi-

ally, shield plates fitting in the grooves of the frame bars, an extension tube having a threaded engagement with the upper connection chamber at one end, and fitting freely at its opposite end in the lateral nozzle of the upper gage cock, a union coupling nut surrounding the extension tube and engaging said nozzle, a gage tube seated on the lateral nozzle of the lower gage cock and fitting freely in the connection chambers, a packing gasket surrounding the gage tube in the upper connection chamber and compressed therein by the extension tube, and a packing gasket surrounding the gage tube in the lower connection chamber and compressed therein by the engagement of said chamber with the lateral nozzle of the lower gage cock.

5. In a water gage for steam boilers, the combination of an upper and a lower gage cock, a gage tube communicating at its opposite ends with the bodies of said gage cocks, a valve chamber interposed between the gage tube and the upper gage cock and having a transverse partition perforated by a port in line with the gage tube, a floating 75 pan normally resting on an inclined face of said partition and having a guide way extending transversely to the gage tube, a spring acting to normally hold said pan in said position, and a ball check valve fitted 80 to traverse in said guide way toward and from a seat on the port of the partition.

6. In a water gage for steam boilers, the combination of an upper and a lower gage cock, a gage tube communicating at its opposite ends with the bodies of said gage cocks, a valve chamber interposed between the gage tube and the lower gage cock and having an upper transverse partition perforated by a port in line with the gage tube 90 and a lower inclined partition perforated by a similar central port and by a lateral port at a lower level than the central port, and a ball check valve resting normally on the lower side of the lower partition and 95 adapted to be seated, by unbalanced pressure from the lower gage cock, on the port of the upper partition.

HENRY C. MANCHESTER.
